UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,324,087.

Specification of Letters Patent.

Patented Dec. 9, 1919.

Application filed April 12, 1919. Serial No. 289,628.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to a new and useful 10 improvement in buttons and particularly to that type of button which is employed with a staple which is adapted to pierce its way through an imperforate base and be guided in its upward movement by an anchor located in said button and to impinge or flatten against the anchor or die to thereby tightly lock the prongs of the staple in the button and also prevent the top plate from being marred or otherwise pierced by the 15 said staple.

The invention relates generally to that 20 type of button for which separate applications have been executed by me of even date herewith.

One of the objects of the present invention 25 is to provide a button provided with an anchor, which anchor in this instance also comprises an anvil or die, so that the said anchor and anvil are rigidly held in position 30 within the button.

Another object of my invention is to provide 35 a novel form of anchor which in this instance comprises a cup or shell portion in which is placed a die to correctly position the prongs of the staple in their upward movement into the button and also to cause the ends of the staple to deflect when they reach their limit of upward movement, and substantially lock in the die.

Still another object of my invention is to 40 provide a button comprising a body portion, a top plate, a shell, and a die within said shell, which shell may be pressed around the die before being placed in the button, the shell and die forming the anchor, and a 45 staple for piercing the body portion of the button and lock in the anchor to rigidly hold the same to the cloth to which it is to be fastened.

Another object of my invention is to provide 50 a button of the above type that will be cheap to manufacture, easy to construct, and quickly and readily assembled.

With these and other objects in view, my

invention consists in certain novel features 55 of construction and combinations of parts as will be hereinafter more fully described and pointed out in the claims.

Referring now to the drawings:

Figure 1 is a sectional view of the button, 60 with the anchor portion, however, being in elevation, and the staple that is used in conjunction with the button also being in elevation;

Fig. 2 is a vertical sectional view showing 65 the staple in its final position;

Fig. 3 is a top plan view of the button with a portion of the top plate and shell removed for the sake of clearness;

Fig. 4 is a perspective view of the shell of 70 the anchor;

Fig. 5 is a perspective view of the die of the anchor;

Fig. 6 is a perspective of the anchor in its 75 position to be inserted within a button;

Fig. 7 is a sectional view of a slightly modified form; and

Fig. 8 is a perspective of the die in the modified form.

Referring now to the drawings which 80 show the improvement on an enlarged scale, it will be seen that the invention consists of a button having the body portion 1 and the downwardly extending hub 2 in the form of a hollow shell. The upper edge of the body portion 1 is slightly flared as at 3, over which is to be passed a top plate 4 which is designed to be wedged tightly over the flared edge 3 after the anchor is placed in the button. The base of the hub is provided with 90 a slight central depression 5 and an annular groove or ring 6 surrounding said depression.

The purpose of the depression 5 and the annular (as viewed from the bottom) depression 6 is for the purpose of correctly directing the prongs 7 of a staple 8 when the same are to be forced through the cloth 9 and into the button.

A novel form of anchor is shown which 100 comprises a circular shell or socket 10 (see Fig. 4) which is slightly less in diameter than the diameter of the hub of the body portion. Fitting snugly within this shell 10 is a die 11 which comprises a shank 12 105 which is enlarged as at 13 where it merges with the top portion 14. This top portion is provided with an outwardly and down-

wardly extending flange 15 for the reception of the prongs 7 when forced into the same.

After this die has been placed into the shell 10, the side walls of the shell are forced inwardly, as clearly shown in Fig. 6, thereby tightly holding the die in its correct position. Furthermore, the walls of the shell act as a guide for the prongs of the staple 10 when forced upwardly, as shown in Fig. 2.

After the anchor is assembled the same will be forced into the hub 2 of the button, as shown in Fig. 2, and the top plate then wedged over the flared edge 3, as heretofore mentioned.

When it is desired to fasten the button to the cloth, the prongs 7 of the staple will pierce the cloth and be properly directed by the side walls of the annular groove 6 and the depression 5, and after piercing the said base will be correctly alined by the shank 12 of the die. Passing upwardly, these prongs will enter between the shank 12 and the side walls of the shell or socket 10 and continue upwardly until they strike the enlarged portion 13 and top portion 14 of the die and will then flatten and impinge against the downwardly extending flange 15 of said die and against the side walls of the shell 10, thereby tightly securing the button, through the base plate and anchor to the cloth.

In Figs. 7 and 8 I have shown a slightly modified form, in this instance doing away with the shell 10 and using a die 16, somewhat similar to the die 11 but having its outwardly and downwardly extending flanged wall 17 extending further inwardly, as at 18. It will be understood that this die may be made by first taking a rivet and forcing the flange 17 straight downwardly, and then inwardly until it assumes the position clearly shown in Fig. 7. A top plate 19 is shown, and a body portion 20 of the button, and the flared side portion 21, and the base 22 is formed exactly as the base is of the preferred form. In other words, the only difference in the two forms is that the shell 10 is dispensed with and the downwardly extending flange 17 is greater in width so that it may be pressed inwardly to assume the position 18 shown in Fig. 7.

From the foregoing it will be seen that I have provided a button that provides a number of points of contact between the prongs of the staple and the button, thereby tightly and rigidly holding the button in its position, and wherein the anchor and die are also tightly held with respect to each other and with respect to the body portion of the button. Also I have provided a button whereby there is no danger of the prongs after perforating the base of the hub becoming deflected, but on the other hand by providing the anchor as above described 65 the prongs of the staple will be correctly

guided throughout their entire passage and to their final position in the anchor of the button. Also by forming the anchor as shown, less metal of a higher quality is needed for the die than is generally used in a button of this nature; the anvil of course being the thickest and hardest metal of the entire button. It will be understood that many slight changes may be made without in any way departing from the scope and spirit of my invention.

Having thus described and explained my invention, I claim and desire to secure by Letters Patent:

1. A button comprising a body portion provided with a downwardly extending hub having an imperforate base provided with an annular groove and a central depression; an anchor fitting within the hub and provided with a downwardly extending shank, a shell forming a part of said anchor, the lowermost edges thereof located above the imperforate base and below the top portion of the anchor; and a top plate secured to said body portion. 90

2. A button comprising a body portion provided with a hub and an imperforate base plate, said base plate being provided with a central depression and an annular ring surrounding the same; an anchor located within said hub portion and comprising a shell; a die fitting within said shell and the lower ends of said shell forced downwardly over said die, said die provided with a central depending shank and of such diameter as to leave a space between the side walls of the shell and said shank; and a top plate secured to said body portion. 95

3. A button comprising a body portion having a hub provided with an imperforate base; an anchor in said hub, said anchor comprising a circular shell and a die provided with a downwardly depending shank, and said shell being bent to inclose and tightly hold said die, the lower edge of said shell being spaced from said depending shank, and a top plate on said button. 105

4. A button comprising a body portion provided with a hub and an imperforate base, said base being provided with indentations; an anchor fitting within said hub and comprising a shell, and a die fitting within said shell, said die comprising a top plate, a downwardly extending flange around the edge of said top plate, and a depending central shank, the ends of said shell being spaced from said depending shank, and a top plate secured to the body portion of the button for tightly holding the anchor in said button. 115

5. A button comprising a body portion provided with a hub, a depression formed in the bottom of said hub, and an annular ring also surrounding said depression; an anchor in said hub comprising a shell, and 130

a die fitting within said shell and provided with a downwardly depending flared shank, and a flange around the upper portion of said die, the ends of the shell being spaced from the dependent shank and extending to a point below the flange portion of said die, and a top plate secured to the body portion for holding the anchor in position.

6. A button comprising a body portion having a hub provided with a base plate, said base plate being imperforate and provided with an annular groove and central depression; an anchor having a die therein located in said button; a staple for entering the imperforate base plate, and means formed around the upper portion of said die for guiding and locking the prongs of said staple when forced into said button.

7. A button comprising in part an anchor, said anchor comprising a shell, a die fitting within said shell, and said shell bent to tightly hold said die in position, and said die provided with a downwardly extending centrally located shank.

8. A button comprising in part an anchor, said anchor comprising a shell, a die fitting within said shell and the side walls of said shell being bent inwardly to retain the said die in said shell, said die provided with a flared downwardly extending side wall and the lower edge of said shell extending below the said flange, and a shank extending from

said die and being spaced from the lower edges of said shell.

9. A button comprising a body portion 35 provided with a downwardly extending hub having an imperforate base provided with an annular groove and a central depression; a die fitting within the hub and provided with a downwardly extending shank, said 40 die provided with a downwardly and inwardly extending flange, and a top plate secured to the body portion of the button.

10. A button comprising a body portion having a hub provided with an imperforate 45 base; an anchor in said hub comprising a die provided with a downwardly depending shank, and an enlarged upper portion provided with a downwardly and inwardly extending rim.

11. A button comprising in part a die having a downwardly depending shank and an upper enlarged portion, said enlarged portion extending downwardly to form a rim and said rim forced inwardly but leaving a space between the edge of said rim and the downwardly depending shank.

Signed at Waterbury, in the county of New Haven and State of Connecticut, this 7th day of April A. D. 1919.

FRANKLIN R. WHITE.

Witness:

EDNA M. MORTON.
